SPARKING PLUG.

1,181,115.

Specification of Letters Patent. Patented Mar. 9, 1915.

Application filed June 9, 1914. Serial No. 844,032.

To all whom it may concern:

Be it known that I, RODOLPHE CARPENTIER, a citizen of the Republic of France, residing at 124th Rue de Paris, St. Denis, Seine, in the Republic of France, have invented certain new and useful Improvements in Sparking Plugs, of which the following is a specification:

This invention relates to improvements in 10 sparking plugs, and has for its object to obviate the trouble caused by the sootting up of the points.

It is known that the plugs for the electric ignition of explosion engines are liable 15 to soot up very readily. The result is that frequently the spark produced is poor and not sufficiently hot or it may even not be produced at all, so that the ignition is not effected. The electrodes between which the 20 spark passes are often arranged in the cylinder end so that they are necessarily liable to be splashed with oil, which, together with the soot, produced by incomplete combustion, form deposits between these electrodes 25 which are sufficient to modify the medium through which the spark passes in such a manner as to produce short circuits and prevent the passage of the spark. In order to obviate this defect multiple spark-plugs 30 have already been constructed in which one of the electrodes is subdivided into a number of branches which may be arranged starwise and terminating at a small distance from an annular electrode connected to earth. In this manner a number of sparks 35 are obtained at several different places, so that they are not liable to be sooted up simultaneously. Nevertheless in a device of this kind, if one of the spaces in which a 40 spark is produced should be sooted up, the current has a tendency to pass more readily through the deposit which is slightly conducting, the result being a short circuit which prevents the other sparks from passing.

A construction according to my invention is broadly characterized by a special arrangement of the electrodes rendering it possible to produce a number of sparks in a condition such that if one of them should fail, as a result of a deposit of soot between two of the electrodes, the other sparks not only continue to pass and maintain the ig-

nition, but they also automatically volatilize and dissipate the carbonaceous deposit 55 so that the spark that has failed, is reestablished.

The novel arrangement consists broadly of one or more groups of electrodes each producing a couple of adjacent sparks. 60 Each group of electrodes is formed of two insulated electrodes of like polarity terminating on either side of and at a small interval from an electrode connected with the mass, in such a manner as to produce two 65 adjacent sparks issuing from the mass-electrode and terminating at the insulated electrodes.

The current is conducted to the electrode of like polarity by the intermediary of a 70 conductor whose position is adjustable and which is placed in communication with one of the poles of the ignition circuit and terminates at a small distance from the two electrodes in such a manner as to produce 75 two supplementary break sparks passing between itself and each of the electrodes. This conductor is adjustably mounted with the object of enabling the explosive distance of the supplementary break sparks to be varied in order to obtain the hottest and fastest sparks possible.

It is known that if one or more gaps be provided at any points in the circuit thereby producing a corresponding number of supplementary break sparks, the ignition spark proper is rendered hotter and more brilliant. Moreover experience has demonstrated that if a plurality of ignition sparks are caused to pass between several electrodes 90 of like polarity insulated one from the other and an earthed electrode the short circuit produced by a deposit of soot on one of the electrodes does not prevent the other sparks 95 from passing provided that each insulated electrode is provided with a gap producing a break spark. It is upon this principle 100 that the novel electrobreak device is based. Moreover, the supplementary break sparks are produced inside a closed cavity formed 105 in the midst of the body of the apparatus in such a manner that they are protected from the air whereby any risk of fire due to the proximity of the spirit reservoir and the carburetor is avoided.

No misfiring is liable to occur with the

- novel ignition device and as already stated the sparks are produced in closely adjacent pairs and if one of them should fail owing to sooting up the other spark continues to pass and is sufficiently hot to dissipate this deposit and reestablish the failing spark. In point of fact the electrodes themselves never become sooted up because the sparks always tend to clean these electrodes and when the engine is stopped, it is found that the deposits of soot are made solely upon the edges of the plug, the electrodes themselves invariably remaining perfectly free from any deposit.
- 15 An embodiment of the invention is illustrated by way of example in the accompanying drawing which represents the device in longitudinal section.

As shown in the drawing, the novel electrobreatk device consists of two central sleeves *a*, *b* of insulating material such as porcelain for example, cemented externally to metal sockets *a'*, *b'*. The socket *b'* ends in a conical portion *b*² and the socket *a'* is threaded for a portion of its length at *a*² in such a manner that the said sockets can be united by a tapped collar *c* presenting a conical internal projection *c'* which fits over the portion *b*². The collar *c* also presents an end *c*² for screwing the device as a whole into the cylinder end. Metal rings *d*, *e* are clamped between the sleeves *a* and *b*.

An inner metal sleeve *f* is fixed axially in the sleeve *a* and ends on the one hand in a shoulder *f'* and on the other hand in a threaded portion *f*². Upon this threaded portion *f*² a fixing nut *g* is screwed while a lock nut *h* serves to lock the rod *i* when it has been adjusted. The interior of the sleeve *f* is threaded throughout its entire length and a threaded metal rod *i* can be screwed into the sleeve *f*. This rod *i* constitutes the break electrode; inside the sleeve *a* it ends in a circular plate *i'* and outside this sleeve in a milled knob *i*² for operating it. Opposite and at a small distance from the plate *i'* three electrodes are embedded in the insulating sleeve *b* a central electrode *j* and two lateral electrodes *k'* and *k*². The central electrode *j* is bent over toward the lower extremity at two points *j'*, *j*² which terminate at a short distance from the end of the electrodes *k'*, *k*² respectively. Finally two other electrodes *l'*, *l*² are connected to earth at a short distance from the electrodes *k'* and *j'* and *k*² and *j*². The central electrode *j* might be divided at two or more points, a corresponding number of electrodes *k* and *l* being arranged throughout the periphery of the insulating portion. Whichever arrangement be adopted, the current is conducted to the central conductor *i* and the electrodes *l*² are earthed.

65 A metal cap *m* clamped between the fiber washer *n* and a shoulder on the sleeve *a*

serves to protect the porcelain of the sleeve *a* from blows and from injury by spanners when fitting.

The novel device acts in the following manner: The distance between the electrodes *k'*, *l'* and *j'*, and *k*², *l*² and *j*² having been adjusted and the current being supplied to the central conductor *i* as already explained assuming first of all that the plate *i'* is in contact with the electrodes *k'*, *k*² and *j* the ignition sparks pass between *k'*, *j'* and *l'* and *k*², *l*² and *j*² and the device acts in the manner of an ordinary sparking plug. If the plate *i'* be then separated slightly from the electrodes *k'*, *k*², *j* break sparks pass between the latter and the plate *i'* and the ignition sparks become hotter. In these conditions as will be understood, it is possible to modify the distance between the plate *i'* and the electrodes to regulate the break sparks of this plate at will and in such a manner that the ignition sparks proper are rendered as hot as possible. Moreover, if sooting should take place on the path for one of the sparks, between *k'* and *l'* for example, the sparks would continue to pass between *j'*, *l'* and between *k*², *l*² and *j*² and *l*² until the sooty deposit is itself dissipated or destroyed by the heat as has been ascertained experimentally.

This apparatus therefore presents the advantage of providing a constant ignition without possibility of failure; moreover as the break spark can be regulated by the distance of the plate *i'* from the electrodes, the ignition sparks can always be produced in the best possible conditions. The sparks are also produced at several places and if one should fail, the others would insure the ignition until the failing spark is reestablished. As already stated in view of the fact that the point of rupture is located in the midst of the device itself, and protected from the air, any risk of fire is absolutely avoided.

What I claim and desire to secure by Letters Patent of the United States is:

1. In an explosion engine, a spark plug adapted to insure the ignition and the spontaneous unsootting of the electrodes, consisting in a group of two insulated adjacent electrodes of like polarity, terminating at a short distance from a third earthed electrode, a conductor adjustable in position, terminating at a short distance from the other ends of the insulated electrodes of like polarity for conducting the current thereto through the medium of supplementary sparks produced between the said conductor and the insulated electrodes of like polarity.

2. In an explosion engine, a spark plug adapted to insure the ignition and the spontaneous unsootting of the electrodes, comprising two insulating sleeves connected by metal sleeves, a closed chamber between the

insulating sleeves, a group of two electrodes of like polarity embedded in the insulation of the lower sleeve, an earthed electrode terminating at a short distance from the insulated electrodes, a central conductor adjustably mounted in the insulation of the upper sleeve and conducting the current to the insulated electrodes of like polarity through the medium of supplementary sparks spring-

ing forth in the closed chamber between the conductor and each of the insulated electrodes.

In testimony whereof I affix my signature in presence of two witnesses.

RODOLPHE CARPENTIER.
